UNITED STATES PATENT OFFICE.

TIMOTHY M. O'CONNELL, OF PHILADELPHIA, PENNSYLVANIA.

DESIGN FOR STATUARY.

Application filed July 29, 1925. Serial No. 14,256. Term of patent 3½ years.

To all whom it may concern:

Be it known that I, TIMOTHY M. O'CONNELL, a citizen of the United States, residing at the city of Philadelphia, in the county of Philadelphia and State of Pennsylvania, have invented a new, original, and ornamental Design for Statuary, of which the following is a specification, reference being had to the accompanying drawing, forming part hereof and in which the figure in the drawing is a view in perspective of my new design for statuary.

I claim:

The ornamental design for statuary, as shown.

TIMOTHY M. O'CONNELL.
